UNITED STATES PATENT OFFICE.

CHARLES R. BIRDSEY, OF HINSDALE, ILLINOIS, ASSIGNOR, BY MESNE ASSIGNMENTS,
TO UNITED STATES GYPSUM COMPANY, OF CHICAGO, ILLINOIS, A CORPORATION
OF ILLINOIS.

PLASTER-BOARD.

1,383,254.

Specification of Letters Patent. Patented June 28, 1921.

Application filed July 29, 1918. Serial No. 247,244.

To all whom it may concern:

Be it known that I, CHARLES R. BIRDSEY, a citizen of the United States, residing at Hinsdale, in the county of Dupage and 5 State of Illinois, have invented certain new and useful Improvements in Plaster-Board, of which the following is a description.

My invention belongs to that general class of devices known as plaster board or the 10 like, and relates particularly to an improved board which will be simple, substantial, durable, satisfactory and efficient, and which may be economically and accurately manufactured. The invention relates particularly 15 to a type of board in which the inclosed plaster, plaster Paris or plastic material is completely inclosed on one or on opposite edges, and in which the edges may be perfectly formed to conform to a definite 20 specification as to size, the edge or edges being straight so that meeting edges of adjacent boards may be brought close together with but a small crack or space between them.

25 To this end, my invention consists in the novel construction, arrangement and combination of parts herein shown and described and more particularly pointed out in the claims.

30 In the drawings, wherein like reference characters indicate like or corresponding parts,

Figure 1 is a perspective view of a portion 35 of the plaster board embodying the invention;

Fig. 2 is a sectional view taken substantially on line 2—2 of Fig. 1;

Fig. 3 is a somewhat similar view illustrating a step in the manufacture in producing 40 a straight edge which will be accurately formed; and

Fig. 4 is a detailed view illustrating how the covering sheet may be scored to facilitate folding or bending thereof.

45 Referring to the drawings, 1 represents a body of suitable material, as for example plaster, plaster Paris or the equivalent suitable for the purpose, which may be handled in a plastic state and thereafter allowed to set or harden. The body is inclosed between the sheets 2 and 3 of suitable covering material, and in this connection it may be mentioned that I have found paper of the desired weight or thickness very satisfactory 50 for the purpose. In making the board a layer or layers of plastic material 1 forming the body of the board is placed on a sheet 2, which is preferably turned up at one or on opposite edges, and the covering sheet 3 placed over the plastic material. During 60 the forming of the board the outer edge or edges of the sheet 2 are preferably turned as at 4—5. After the plastic material forming the body 1 is placed on the board and the covering sheet 3 placed over it, the extreme outer edge or edges 5 of the lower sheet are turned over the body so as to overlie the outer edges 6 of the sheet 3. Edge 5 is secured to the edge 6 in any suitable manner, preferably by allowing a portion 70 of the plastic material to flow between the two sheets during the manufacture of the board. Where plastic material of the kind described is used as the body 1, this will serve as a seal and efficiently secure the two 75 sheets together at this point. The portion 5 may be forced down or depressed so as to offset the part 6 as indicated at 11 in Fig. 2, so as to produce a finished product, with part 5 and the body sheet 3 flush. 80

The sheet 2 is supported flat and maintained flat by the body 1, and when sheet 3 is applied in the manufacture of the board the same is supported by the body and tends to adhere thereto. This being the case, the 85 sheet 3 at this time tends to partake of the stiffness of the body. That is to say, pressure applied to the edge of the sheet 3, for example as at the point 10 (see Figs. 2 and 3), will not only have the normal stiffness 90 of the paper to push against, but owing to the adhering of the paper to the body 1 there will be but slight tendency for the paper to crumple up, as it will be held down by the body. The result therefore is that 95 the edge of the sheet 3 at the point 10 acts substantially as a straight edge over which the end 5 may be bent. Ordinarily it is preferred to score the sheet 2 as at 8 and 9 to facilitate the bending to form the edge 4 100 of the board and the top of the overlying portion 5. Any material that seeps through as at 10, while ordinarily slight, is spread over the edge 6 to the under sheet by the bending down of the edge 5 of the sheet 2, 105 thus securing edge 5 to edge 6. Ordinarily in the manufacture, opposite edges of the continuous board are formed similar to that illustrated in the drawings. The distance between the scorings 8 at each side of the 110

board may be accurately gaged as desired. This is also true of the cover sheet 3. Consequently, when the part 5 is turned over the edge 4 is formed accurately in a predetermined manner without any rolling or curve, for example, without any half round effect. In turning down edge 5 there may be a possibility of the end 6 being pushed in a little at the free edge, but ordinarily this is insufficient to affect the gaging and vary the straight edge action.

In Fig. 2 I have illustrated in dotted lines the edge 6 turned slightly downward, this being possibly an exaggerated instance. However, this takes effect practically at the last step of the manufacture, and even then the downward depressing of end 6 is hardly sufficient to affect the gaging or straight edge action. In this connection, should end 6 be turned down as shown and indicated by the numeral 6', there is no weakening of the board, as almost the entire body is present except possibly at the extreme edge of the sheet 3, at which point a slight reduction in the amount of material would not be harmful. In any event, the board would be stiff owing to the full amount of material between the edge 5 and the bottom. This might be perhaps better understood by stating that a board is not easily broken at the extreme edge, but may at times be easily broken farther in from the edge. In the present case, however, assuming that in manufacture end 6 did occasionally become depressed, this would be immaterial as the board to all practical purposes would not be weakened.

By manufacturing a board as described the resulting product is produced with a straight, smooth edge and at a perfect angle, the board being uniform in width throughout its length. The completed product has numerous advantages, among which may be enumerated increased strength and durability, and an improved appearance. If any of the plastic sealing material flows beyond the free edge 5, the same is spaced back from the edge of the board so that all of the extreme edges of the board are of pleasing appearance and perfectly true, there being no protruding plastic material on the edge. The extending of the cover sheet 3 to the extreme edge of the board gives the full strength of the sheet from edge to edge. This is true for both cover sheets, and in case of any strain from contraction or expansion of the board, or sheets in manufacture or otherwise, the effect is uniform throughout the faces of the board. Should it happen that from lack of sufficient plastic material at 7, part 5 should not adhere perfectly to sheet 3, the appearance and strength of the board and its utility would not in any way be impaired. In fact, side part 4 of sheet 2 would be maintained in place by its

adherence to the body and be strengthened by its engagement with the edge of the sheet 3, even if not securely fastened on the outer face of cover sheet 3. However, in this case, the material is inclosed and protected, and at the extreme edge of the board there are no exposed edges of sheets 2 or 3 which might be accidentally peeled back. Likewise, the edge is finished and trimming of the side edges of the board with resulting waste and additional expense is entirely obviated.

Having thus described my invention, it is obvious that various immaterial modifications may be made in the same without departing from the spirit of my invention; hence I do not wish to be understood as limiting myself to the exact form, construction, arrangement and combination of parts herein shown and described or uses mentioned.

What I claim as new and desire to secure by Letters Patent is:—

1. A plaster board comprising a body, a relatively stiff covering sheet of fibrous material adhering to one face of the body and extending to adjacent one edge of the body, and a second covering sheet adhering to the other face of the body and having an extension at one side folded over to inclose the edge of the body and overlie a portion of the body and the edge portion of the first covering sheet.

2. A plaster board comprising a body, a relatively stiff covering sheet of fibrous material adhering to one face of the body and extending to adjacent one edge of the body, and a second similarly relatively stiff covering sheet adhering to the other face of the body and having an extension at one side folded over to inclose the edge of the body and overlie a portion of the body and the edge portion of the first covering sheet.

3. A plaster board comprising a body, a relatively stiff imperforate covering sheet of fibrous material adhering to one face of the body and extending to adjacent one edge of the body, and a second covering sheet adhering to the other face of the body and having an extension at one side folded over to inclose the edge of the body and overlie a portion of the body and the edge portion of the first covering sheet.

4. A plaster board comprising a body, an imperforate covering sheet adhering to one face of the body and extending to adjacent one edge of the body, and a second covering sheet adhering to the other face of the body and having an extension at one side folded over to inclose the edge of the body and overlie a portion of the body and the edge portion of the first covering sheet.

5. A plaster board comprising a body, an imperforate covering sheet adhering to one face of the body and extending to adjacent one edge of the body, and a second imperforate covering sheet adhering to the other

face of the body and having an extension at one side folded over to inclose the edge of the body and overlie a portion of the body and the edge portion of the first covering sheet.

6. A plaster board comprising a body, a relatively stiff imperforate covering sheet of fibrous material adhering to one face of the body and extending to adjacent one edge of the body, and a second relatively stiff imperforate covering sheet adhering to the other face of the body and having an ex-

tension at one side folded over to inclose the edge of the body and overlie a portion of the body and the edge portion of the first covering sheet.

In testimony whereof, I have hereunto signed my name in the presence of two subscribing witnesses.

CHARLES R. BIRDSEY.
